UNITED STATES PATENT OFFICE

ADEN E. SMITH, OF COLUMBUS, OHIO, ASSIGNOR TO THE D. A. EBINGER SANITARY MFG. CO., OF COLUMBUS, OHIO, A CORPORATION OF OHIO

REFRIGERATED BOTTLE DISPENSER

Application filed November 11, 1927. Serial No. 232,684.

This invention relates to improvements in refrigerated bottle dispensers, and is particularly directed to a bottle dispenser wherein an improved arrangement is provided for 5 storing a relatively large quantity of bottles and to permit of the withdrawal of the bottles from the dispenser at positions contiguous to the coolest zone of the dispenser.

The invention contemplates further the 10 provision of a dispenser in the form of a cabinet having heat insulated walls and wherein the interior of the cabinet is formed to comprise a plurality of bottle containing compartments, which are separated by thin metallic walls from the cooling compartment of the 15 cabinet which is adapted to receive mechanical refrigerating units or any other equivalent cooling medium, the bottle receiving compartments being each provided with a rack 20 provided with a zig-zag or staggered guide capable of receiving a suitable quantity of bottles, and the bottom of each bottle compartment is provided with a movable closure or door which, when opened, permits of the 25 withdrawal of the lower bottle from the dispenser, the arrangement being such that a plurality of bottles are received within each bottle compartment and are permitted to gravitate toward the bottom thereof in a controlled manner as the bottles are individually 30 withdrawn from the bottom of the compartment, the construction serving to permit the bottles to be handled without damage or breakage, to enable the bottle possessing the 35 lowest temperature to be withdrawn from the container and to permit of the dispensing of various kinds of beverages in a separate and easily regulated manner.

With these and other objects in view, as will appear as the description proceeds, the invention consists in the novel features of construction, combinations of elements and arrangements of parts hereinafter to be more fully described and pointed out in the appended claims.

In the accompanying drawing:

Figure 1 is a view partly in front elevation and partly in vertical section of the improved bottle dispenser comprising the present invention,

Figure 2 is a horizontal sectional view taken on the plane indicated by the line 2—2 of Figure 1,

Figure 3 is a side elevation of the bottle dispenser, the lower portion thereof being 55 broken away to disclose internal construction,

Figure 4 is an enlarged vertical sectional view taken through one of the bottle compartments and showing in greater detail the 60 staggered bottle guideways formed therein.

Referring more particularly to the drawing the numeral 1 designates in its entirety the casing or housing of my improved bottle dispenser. The preferred form of this casing 65 comprises a double wall, box like structure having a bottom 2, end walls 3, front and back walls 4 and 5 respectively and a removable top wall 6. Each of these walls consists of two thicknesses of metal between which are 70 situated cork board or other heat insulating material. Interiorly the housing or casing is formed to include a refrigerant compartment 7 which is adapted in certain embodiments of my invention to receive mechanical refrigerating units 8, or, if desired, the compartment 7 may receive ice, solidified carbon 75 dioxide or any other cooling medium.

Situated within the refrigerating compartment 7 and disposed adjacent to the front 80 wall 4 of the casing are a number of bottle receiving compartments 9, which are formed in this instance by means of metallic walls 10, which are of substantially U shaped form 85 when viewed in plan, and extend substantially the full height of the compartment 7. The walls 10 of adjacent compartments 9 are separated to permit of complete circulation of the refrigerating medium around at least 90 three full sides of each compartment. The front of the compartments 9 are closed by the position of the inner wall or surface of the front wall 4, the arrangement preventing the refrigerating medium from coming into 95 direct contact with the commodities positioned within the bottle compartment.

Arranged to be positioned within each of the compartments 9 is a bottle holder or rack 11, which can be inserted within the compartments or removed therefrom by way of 100

the removable top wall 6. These racks or holders are of peculiar design and, as shown more particularly in Figures 1 and 4, each of these racks has fixed therein a plurality of substantially triangular shaped members 12, the apices of which being disposed in offset relationship with respect to one another so that each rack provides a bottle receiving channel 13 of substantially zig-zag form. 5

10 This arrangement permits the bottle to be inserted horizontally within each rack up to the full holding capacity of the channel 13, and the construction is such that upon the removal of the lower bottle contained within each rack, the bottles above the same will 15 gravitate slowly yet positively in a downward direction so that there is always a bottle at the extreme lower end of the channel. Inasmuch as this is the coldest part of each compartment 9, it follows that the bottle withdrawn from the rack will possess the lowest 20 temperature and will therefore be more suitable for beverage purposes. The racks may be filled with bottles when disposed exteriorly 25 of the dispenser and may then be inserted as a group into the casing, where the bottles may be applied without necessarily removing each rack. A sufficient number of compartments and racks has been provided to permit 30 the merchant to handle a variety of different beverages and the construction insures the delivery of bottles having the contents thereof chilled to the requisite extent. As shown in 35 Figure 4 the bottles are arranged within the rack in relatively angular order on frames disposed at substantially 30 degrees with respect to the horizontal. This enables the bottles to work downwardly in the relatively slow but positive manner desired and prevents the same from sticking or jamming 40 within the channel 13.

To remove the bottles the front wall 4 of the casing, contiguous to the bottom wall 2, is provided with a multiplicity of openings 45 14, which are arranged in registration with the extreme lower end of the bottle compartment 9. These openings are closed normally by means of individual doors 15, which are formed to include spring hinge mountings 16. 50 By lowering the doors a bottle may be withdrawn from the respective compartments governed thereby with ease and convenience. The casing has been shown as mounted upon supporting legs 17. It will be appreciated, 55 however, that any suitable type of supporting base may be utilized and that the bottom of the casing may be situated at any desired height or horizontal plane above the floor level. This construction assures the delivery 60 of dry bottles.

In view of the foregoing it will be seen that the present invention provides a simple, substantial and easily operated bottle dispenser which may be used particularly by merchants 65 engaged in the business of selling bottled and

refrigerated beverages. The construction enables the merchant to quickly fill hurriedly given orders, particularly during rush periods of business, and yet the customer is assured that the bottle so dispensed will possess 70 a proper temperature.

While I have described what I consider to be the preferred form of the present invention, nevertheless it will be understood that various changes may be made in the form and design of the dispenser, without necessarily departing from the spirit and scope of the invention as the latter has been set forth in the following claims.

What is claimed is:

1. A bottle dispenser comprising a casing formed to include heat insulated walls, said casing being formed internally to include a refrigerant receiving chamber and a plurality of bottle receiving compartments, a removable rack positioned within each of said compartments and adapted for the reception of a plurality of horizontally arranged bottles, each of said racks being formed to include a bottle receiving channel of substantially zig-zag form wherein adjacent bottles impinge upon one another but do not occupy the same vertical plane, and means provided in connection with said casing permitting of the removal of bottles from the lower ends of each 95 of said bottle compartments.

2. A bottle dispenser comprising a casing formed to include heat insulated walls, said casing being provided internally with a refrigerant receiving chamber and a plurality 100 of bottle receiving compartments arranged vertically against one of the side walls of said casing, the walls of said compartment being relatively spaced, a removable bottle receiving rack positioned within each of said compartments, each of said racks being formed to include a bottle receiving channel so formed that the bottles positioned horizontally therein occupy angular positions with respect to adjoining bottles, and means 110 provided in said casing contiguous to the bottom of said compartment permitting of the removal of bottles from said compartments.

3. A bottle dispenser having a casing formed to include heat insulated walls, said casing being formed internally to include a refrigerant receiving chamber and a plurality of vertical bottle receiving compartments extending substantially throughout the height of the refrigerant chamber, a removable rack positioned within each of said compartments and adapted for the reception of a plurality of horizontally arranged bottles, each of said racks being formed to receive a bottle receiving channel of substantially zig-zag form wherein adjacent bottles impinge upon one another but do not occupy the same vertical plane, means provided in connection with said casing permitting of the removal 120 of bottles from the lower ends of each said 125

130

bottle receiving compartments, and means provided in the top of said casing permitting of the removal of each of said removable racks.

- 5 4. A bottle dispenser comprising a casing formed to include heat insulated walls, said casing being provided internally with a refrigerant receiving chamber and a plurality of bottle receiving compartments arranged vertically against one of the side walls of said casing, the walls of said compartments being relatively spaced, a removable bottle receiving rack positioned within each of said compartments, each of said racks being formed to
- 10 include a plurality of substantially angular shaped members the apices of which being disposed in offset relationship with respect to one another providing a bottle receiving channel so that the bottles positioned horizontally therein occupy angular positions with respect to adjoining bottles, means provided in said casing contiguous to the bottom of said compartments permitting of the removal of bottles from said compartments and
- 15 means provided in the side of said casing permitting of the removal of each of said bottle receiving racks.
- 20 5. A bottle dispenser having a casing formed to include an internally disposed refrigerant receiving chamber, a plurality of vertical bottle receiving compartments disposed adjacent to one of the side walls of said casing, each of said bottle receiving compartments being surrounded on three sides
- 25 by the refrigerant receiving chamber and each of said bottle receiving compartments being provided with a bottle channel having relatively off-set angularly disposed walls which produce a channel of substantially zig-
- 30 zag form, said channel being adapted to receive bottles arranged horizontally therein and in such manner that the bottle immediately above a given bottle will impinge upon said given bottle but will occupy a vertical plane off-set angularly from the vertical plane of said given bottle and means formed
- 35 in connection with the lower part of said casing for permitting of the withdrawal of bottles from said compartment.
- 40 50 In testimony whereof I affix my signature.
ADEN E. SMITH.
